UNITED STATES PATENT OFFICE.

FREDERICK W. WEIHE, OF BYRON, CALIFORNIA.

PULLMAN CAR.

Application filed October 11, 1927. Serial No. 225,446.

- This invention relates to improvements in sleeping cars and like structure, and particularly to the arrangement of the beds or bunks therein.
- 5 Railroad sleeping cars are now being made with individual and separate compartments, each having its own bed, so that the occupants of the various compartments are secluded and have the desired privacy.
- 10 With the present bed and compartment arrangement, however, comparatively few travelers can be accommodated in any one car, and consequently the great weight and length of the car entails manufacturing and 15 hauling costs out of all proportion to the income derived, as is well appreciated by those in the business.
- The principal object of my invention therefore is to provide a bed and compartment arrangement in a car of this character such that without increasing the length of the car and without materially increasing its weight, the number of compartments in the car, and consequently the number of 25 passengers which may be carried, is considerably increased over what is at present possible. At the same time each passenger has the same privacy as is obtainable with the present compartment arrangement.
- 30 A further object of the invention is to provide a relatively simple and inexpensive structure and yet one which will be exceedingly effective for the purpose for which it is designed.
- 35 These objects I accomplish by means of such structure and relative arrangement of parts as will fully appear by a perusal of the following specification and claim.
- In the drawings similar characters of reference indicate corresponding parts in the several views:
- 40 Fig. 1 is a fragmentary side view of a sleeping car partly in section to show my improved compartment and bed arrangement.
- 45 Fig. 2 is a fragmentary top plan view of the car taken on the line 2-2 of Fig. 1.
- Referring now more particularly to the characters of reference on the drawings, the 50 main structural features and arrangement of the car 1 are the same as at present constructed; a dressing room 2 for the male occupants being located at one end of the car and a similar room for the female occupants being located at the opposite end of the car, the compartments being located
- between different dressing rooms. Also as is usual in compartment cars a continuous passage 3 extends the full length of the car between the end vestibules, said passage being formed between one side of the car and a longitudinal partition 4 which extends from the floor to the roof. Between said partitions and the opposite side of the car the sleeping compartments are located.
- Extending from said partition to the opposite side wall of the car are transversely disposed lower beds 5, arranged in longitudinally spaced relation and even distances apart. Transverse partitions 6 are spaced 70 equal distances between each pair of beds and extend between the longitudinal partition 4 and the opposite side of the car.
- Located directly above the beds 5 at a height so as to be clear of the windows 7 are upper beds 8 parallel to and the same length as the beds 5. Each upper bed, however, is separated from the corresponding lower bed by a transverse partition structure 9, which extends from the roof 80 down to the bottom of the upper bed along one side thereof; thence under said bed and down to the floor along the opposite side of the lower bed, as plainly shown in Fig. 1. It will therefore be seen that each bed is 85 disposed in a compartment which is completely separated from any other bed, alternate compartments 10 having lower beds, while the intermediate compartments 11 have upper beds.
- The partition 4 has a door 12 for each compartment, while the partitions 6 may if desired each have a door 13 so as to enable a number of adjacent compartments to be arranged en suite. The windows 7, which as customary are disposed in adjacent pairs, 90 are arranged so that each compartment has one window. The lower beds form seats for day travel, while the compartments having the upper beds therein would be provided with a suitable form of folding or other type of chair to accommodate the occupants of the corresponding compartments in the day time.
- 95 While I have shown and described this arrangement as particularly intended for sleeping cars, it is obvious that such arrangement will be also useful in any place where space is limited and privacy is desired; such as in passenger boats, air-ships 100 cabins, as well as possibly the bunk houses such as are erected for the use of workers

in orchards and the like, and in apartment houses.

From the foregoing description it will be readily seen that I have produced such a structure as substantially fulfills the objects of the invention as set forth herein.

While this specification sets forth in detail the present and preferred construction of the structure, still in practice such deviations from such detail may be resorted to as do not form a departure from the spirit of the invention, as defined by the appended claim.

Having thus described my invention what I claim as new and useful and desire to secure by Letters Patent is:

A sleeping structure comprising spaced side walls, longitudinally spaced vertical partitions extending between the walls, transverse upper and lower beds extending 20 between the side walls and disposed centrally between adjacent partitions, a transverse rigid partition structure arranged to divide the space between adjacent vertical partitions into two compartments one of 25 which has the upper and the other the lower bed therein, and windows in one side wall arranged as spaced pairs; the windows of each pair communicating individually with adjacent compartments. 30

In testimony whereof I affix my signature.

FREDERICK W. WEIHE.
